Filed Aug. 13, 1973, Ser. No. 388,023

Term of patent 14 years

Int. Cl. D8—07

U.S. Cl. D8—229

FIG. 1

FIG. 2

FIG. 1 is a side elevational view of a loop-forming cord fastener showing my new design thereof;

FIG. 2 is an exploded front perspective view thereof looking from a point above the loop-forming cord fastener according to my new design.

The side opposite, not disclosed, in both FIGS. 1 and 2 is the same as that side shown in both of the figures. The broken lines in FIG. 1 are for illustrative purposes only.

I claim:

The ornamental design for a loop-forming cord fastener, as shown.
